UNITED STATES PATENT OFFICE

116,823

DESIGN FOR A CIGARETTE DISPENSER

Adolf Huesing, Passaic, N. J.

Application June 3, 1939, Serial No. 85,325

Term of patent 7 years

To all whom it may concern:

Be it known that I, Adolf Huesing, a citizen of the United States, residing in Passaic, in the county of Passaic and State of New Jersey, have invented a new, original, and ornamental Design for a Cigarette Dispenser, of which the following is a specification, reference being had to the accompanying drawing, forming a part thereof.

In the drawing:

In the ornamental design herein shown, the rear wall opposite to the wall shown in Figure 1, consists of a plain panel disposed between two pillars such as illustrated at the front of the dispenser; and the end of the article opposite that shown in Figure 2 is a duplicate of the latter, except that the handle is omitted.

I claim:

The ornamental design for a cigarette dispenser, as shown and described.

ADOLF HUESING.
